VALVE MECHANISM

Charles E. Gates, Elyria, Ohio, assignor to Bé-
dix-Westinghouse Automotive Air Brake Com-
pany, Elyria, Ohio, a corporation of Delaware

Application December 8, 1943, Serial No. 513,424

12 Claims. (Cl. 277—20)

1

This invention relates to fluid pressure control valve mechanism, and more particularly to a control valve of the type having a single operating lever and wherein a plurality of control valve mechanisms are included in a single unit and are adapted to selectively control a plurality of actuators.

It has previously been proposed to utilize control valves of this general type for the purpose of selectively obtaining a finely graduated control of the pressure of fluid supplied to a plurality of actuators, each of the control valve mechanisms comprising the unit being of the self-lapping type wherein a pressure responsive element is moved in one direction in response to the pressure supplied to the actuator for controlling the valve operation, movement in the other direction being accomplished by means of a resilient connection interposed between the pressure responsive element and the control lever, a resilient connecting link or graduating spring thus being required for each separate control valve mechanism in the unit, and it is accordingly an object of the present invention to provide valve mechanism of the above character wherein a single resilient means or graduating spring acts as a yielding connecting link between the control lever and the various pressure responsive elements.

Another object of the present invention is to provide, in a structure of the above type, means whereby the pressure of fluid delivered by a plurality of valve mechanisms in a single unit may be controlled by means of a single graduating spring.

A further object of the invention is to provide, in connection with a control valve of the above type, means for preloading the single graduating spring in order to provide for the delivery of a predetermined pressure by any one of the control valve mechanisms in the unit in response to operation thereof by initial movement of the control lever.

In valves of the above type, it is necessary to provide an opening in the casing around the control lever in order to permit unrestricted movement of the latter, the result being that foreign substances are often introduced into the casing through this opening with resultant damage to the valve mechanism and possible interference with the satisfactory operation thereof, and it is a further object of the invention to provide simple and efficient means for closing this opening in order to overcome this undesirable condition.

A still further object is to provide, in a control

2

valve of the above type, means for automatically maintaining the control lever in its neutral and valve operating positions.

These and other novel features of the invention will be more readily apparent when considered in the light of the accompanying description and drawing. It is to be expressly understood, however, that the drawing is employed for the purposes of illustration only, reference being had, therefore, to the appended claims for a definition of the limits of the invention.

In the drawing,

Fig. 1 is a sectional view of a control valve constructed in accordance with the principles of the present invention;

Fig. 2 is a top view indicating the arrangement of the various valve mechanisms comprising the unit, and

Fig. 3 is a fragmentary view of a portion of the 20 detent mechanism associated with the control mechanism.

Referring more particularly to Fig. 1, the valve unit is shown as comprising a casing 4 provided with an inlet chamber 5 connected with any suitable source of fluid pressure, not shown, by means of conduit 6. As indicated more particularly in Fig. 2, the control valve unit is preferably provided with a plurality of separate valve mechanisms 25 symmetrically arranged about the vertical center line of the casing, the circles shown in dotted lines on Fig. 2 serving to indicate the preferred arrangement of four of these valve mechanisms in a single unit. These valve mechanisms are of identical construction and referring 30 again to Fig. 1, such a valve mechanism is designated at the right hand side of the drawing by the numeral 7.

The right hand portion of the casing is provided with a bore 8, this bore being divided into 40 exhaust and outlet chambers 9 and 10 respectively by means of a pressure responsive valve operating element 11 slidably mounted in the bore. The element 11 is provided with an upwardly extending stem 12 for the purpose of operating the element, and the lower portion of the element is provided with a centrally located bore 13. The outlet chamber is separated from the inlet chamber 5 by means of a ported partition 14, the flow of fluid pressure between the chambers being normally prevented by means of an inlet valve 15 having an upwardly extending stem 16 and an exhaust valve 17 carried on the upper end of the stem. The inlet valve is normally maintained in the port closing position 50 shown by means of an inlet valve spring 18 inter-

posed between the upper side of the partition and the lower side of the exhaust valve. A spring 19 is interposed between the partition and the lower side of the pressure responsive element 11, and normally serves to maintain the element in the position shown, whereby the lower end of the bore 13 is spaced from the upper surface of the exhaust valve. The lower end of the piston is provided with a guide portion 20 surrounding the exhaust valve and communication between the outlet chamber and bore 13 is provided by means of ports 21 formed in the wall of the guide portion, the upper end of the bore 13 being in communication with the exhaust chamber by means of a port 22, and the exhaust chamber in turn being connected to atmosphere by means of a suitable outlet conduit 23. Thus with the parts in the position shown, the inlet valve serves to prevent communication between the inlet and outlet chambers, while the exhaust valve serves to permit communication between the outlet chamber and atmosphere through the ports 21, the bore 13, the port 22, the exhaust chamber 9 and the outlet conduit 23. When the plunger 12 is moved downward, the lower end of the bore 13 first engages the exhaust valve, further movement of the plunger serving to open the intake valve in order to permit communication between the inlet chamber and the outlet chamber through the ported partition 14, the outlet chamber in turn being connected to the desired actuator, not shown, by means of an outlet conduit 24. In like manner there is illustrated in the left hand portion of Fig. 1, a similar valve mechanism having an outlet chamber 25 connected with a second actuator, not shown, by means of a conduit 26, and an exhaust chamber 27 connected with atmosphere by means of an outlet conduit 28, communication between these various chambers being controlled by means of inlet and exhaust valves 29 and 30 actuated by means of a pressure responsive element 31 identical in construction with the element 11 previously described. This valve mechanism may be indicated by the numeral 32 and with reference to Fig. 2 it will be noted that two additional valve mechanisms 33 and 34 are symmetrically arranged in a plane preferably at right angles to the plane passing through the vertical axes of the valve mechanisms 11 and 32.

The pressure responsive element 31 is likewise provided with an upwardly extending stem 35, and it will be understood that the valve mechanisms 33 and 34 are likewise provided with pressure responsive elements and corresponding upwardly extending stems which serve to control the operation of the inlet and exhaust valves incorporated in these mechanisms. In order that the operation of these valve operating element stems may be suitably controlled by the operator, the casing is provided with a ball socket 36 adapted to engage a ball 37 formed on the lower end of an operator's control lever 38, the lever thus being adapted for universal movement with respect to the casing. A suitable cover 39 is suitably secured to the upper portion of the casing, the center portion of the cover being provided with an opening 40 in order to permit movement of the lever in any desired direction from the vertical position shown, and it will be noted, with further reference to Fig. 2, that this opening may, if desired, take the form of right angularly positioned slots 41 and 42 positioned respectively in line with the valve mechanisms 33 and 34 and 11 and 32 respectively, in order to guide the lever

during selective operation of the various valve mechanisms. An operating connection between the lever and the operating plungers of the valve mechanisms 32, 33, 11 and 34 is provided by means of a disc 43 slidably mounted on the lever 38 by means of a bore 44 provided in the disc, and preferably restrained from further downward movement on the lever by means of a shoulder 45 formed thereon. Thus, on movement of the lever in a clockwise direction about the ball 37, the disc will act as a lever to impart downward movement to the plunger 12 and as soon as the intake valve is opened in the valve mechanism 11, the fluid pressure in the outlet chamber 10 will tend to force the plunger upward, with a corresponding tendency to force the disc upward along the lever, at the same time permitting closing of the intake valve in the valve mechanism 11. In order to control this action and to permit the valve mechanism 11 to deliver a pressure substantially proportional to the degree of movement of the lever 38 from neutral position, a resilient member or graduating spring 46 is interposed between the upper surface of the disc and the lower surface of a washer or collar 47 slidably mounted on the lever and having its upper surface in contact with the inner surface of the cover 39, these surfaces being spherically formed with respect to the center of the socket 36, and the collar being of such diameter as to close the opening 40 regardless of the position occupied by the control lever. Thus the graduating spring 46 acts to maintain the collar 47 in engagement with the inner surface of the cover, and at the same time serves, on movement of the lever in a clockwise direction, as a graduating spring for the valve mechanism 11 in order to permit upward movement of the valve element 11 when the pressure in the outlet chamber 10 reaches a value corresponding to the compressing action exerted on the graduating spring by such movement of the lever. In like manner, rotation of the opposite direction will cause the disc 43 to act as a lever to move the plunger 35 downward, and as the pressure increases in the outlet chamber 25 of the valve mechanism 32, will force the element 31 and its connected plunger 35 upward with corresponding upward movement of the disc on the lever 38, until such time as the force exerted by the fluid pressure acting on the element is balanced by the graduating spring force exerted downward on the disc 43. While the graduating spring 46 is not necessarily of the preloaded type, it will be readily understood that the tension of the spring may be so chosen as to cause it to be precompressed when assembled between the disc 43 and the collar 47, downward movement of the disc under this type of operation being prevented by the shoulder 45. Thus on movement of the lever to operate the valve mechanism 11, for example, no movement of the disc 43 with respect to the lever 38 will occur until such time as the pressure in the outlet chamber of the valve mechanism has reached a value sufficient to overcome the pre-loading of the spring, and the pressure delivered on initial movement of the lever will thus correspond to the degree of preloading of the graduating spring, any further increase in pressure in the outlet chamber being proportional to the further degree of movement of the control lever.

It is also desirable to provide means for automatically maintaining the control lever in neutral and valve operating positions, and this is accomplished in the present instance by means of a detent member 48 slidably mounted in a guide

49 carried by the casing, and normally urged upward into engagement with the lower surface of the ball 37 by means of a spring 50. The center portion of the ball is provided with a depression 51 adapted to engage the upper end of the detent member 48 when the lever is in neutral position, together with a groove 52 adapted to engage the detent whenever the lever is moved to its extreme position from neutral in any desired direction, the spring 50 being so tensioned as to insure the 10 maintenance of the lever in one or the other of these positions until moved to another position by the operator.

There has thus been provided by the present invention novel control valve means wherein a plurality of control valve mechanisms may be selectively operated under the control of a single lever, and wherein a self-lapping action of the different valve mechanisms is secured by means of the pressure responsive elements associated therewith operating in cooperation with a single graduating spring which forms a part of a resilient operating link between the control lever and the operating plungers of the various valve mechanisms. Thus a number of expensive parts are eliminated, and a relatively cheap and efficient selectively operable multiple control valve unit is provided which is adapted for the control of a plurality of remotely situated fluid actuators.

While only one embodiment of the invention 30 has been illustrated herein, other arrangements will suggest themselves to those skilled in the art, and it is to be expressly understood that the same is not limited to the forms shown but is capable of being embodied in various other forms without departing from the spirit of the invention. Reference will, therefore, be had to the appended claims for a definition of the limits of the invention.

What is claimed is:

1. The combination in a fluid pressure control valve having a casing and a pair of control valve mechanisms mounted in said casing each provided with inlet and exhaust valves and a pressure responsive element movable for actuating said valves, of means for selectively controlling the operation of said valve mechanisms including a lever mounted on the casing for rocking movement with respect thereto, a member carried by the lever for actuating said elements and mounted for movement with respect to the lever, and means including a resilient member interposed between said first named member and casing for opposing movement of said member with respect to said lever, whereby the degree of pressure delivered by each valve mechanism is proportional to the degree of movement of said lever.

2. The combination in a fluid pressure control valve having a casing and a pair of control valve mechanisms mounted in said casing each provided with inlet and exhaust valves and a pressure responsive element movable for actuating said valves, of means for controlling the operation of said valve mechanisms, including a lever mounted for rocking movement with respect to the casing, a member interposed between the lever and elements for operating the latter and mounted for movement relative to the lever, and a resilient member associated with said first named member and lever for opposing said relative movement, whereby the pressure delivered by each valve mechanism is proportional to the degree of movement of the lever.

3. The combination in a fluid pressure control valve having a casing provided with a plurality

5 of separate control valve mechanisms each provided with inlet and exhaust valves and a manually operable pressure responsive element for controlling the operation of the valves, of means for selectively actuating said elements for controlling the operation of the corresponding valve mechanisms including a lever mounted for universal movement with respect to the casing, a movable member carried by the lever and adapted for engagement with the elements, an abutment mounted on said lever, and a resilient member interposed between said abutment and movable member.

4. The combination in a fluid pressure control valve having a casing provided with a plurality of separate control valve mechanisms each provided with inlet and exhaust valves and a manually operable pressure responsive element for controlling the operation of the valves, of means for selectively actuating said elements for controlling the operation of the corresponding valve mechanisms including a lever pivotally mounted on the casing, a valve operating member slidably mounted on the lever and adapted for engagement with said elements, an opening in the upper portion of the casing for permitting rocking movement of the lever relative to the casing closure means for said opening slidably mounted on the lever and adapted to engage the casing to close said opening, and resilient means interposed between said valve operating member and closure member for maintaining the latter in engagement with the casing and for opposing sliding movement of the former with respect to the lever on rocking movement of the lever to operate the valve operating elements.

5. The combination in a fluid pressure control valve having a casing and a pair of control valve mechanisms mounted in said casing each provided with inlet and exhaust valves and a pressure responsive element for actuating said valves, of means for selectively actuating said elements including a lever pivotally mounted on the casing for rocking movement with respect thereto having a neutral position and movable in different directions from neutral position to actuate one or the other of said elements, a member carried by the lever and movably mounted thereon for connecting said lever and elements, and preloaded

40 resilient means associated with said member and lever for opposing movement of the member with respect to the lever with a predetermined force, whereby on initial movement of the lever from neutral position to operate one or the other of the 45 valves the pressure delivered by the operated valve is proportional to the degree of preloading of the resilient means, and on further movement of the lever is proportional to the degree of further movement.

6. The combination in a fluid pressure control valve having a casing and a pair of control valve mechanisms mounted in said casing each provided with inlet and exhaust valves and a pressure responsive element movable for actuating

65 said valves, of means for selectively moving said elements including a lever pivotally mounted on the casing and movable in one direction or the other to operate one or the other of said elements, and means for transmitting force from said lever to said elements including an abutment member movably carried by the lever and adapted to engage the elements, a second abutment member carried by said lever, and a resilient member interposed between said abutment members.

7. The combination in a fluid pressure control

valve mechanism having a casing and a plurality of control valve mechanisms mounted in the casing each provided with inlet and exhaust valves and a pressure responsive element movable for actuating said valves, of means for selectively operating said element including a lever movable in one plane for operating one or the other of a pair of said elements and in another plane for operating another of said elements, means for guiding said lever for movement in said planes, and means for effecting a yielding force transmitting connection between said lever and elements including a member movably mounted on the lever and adapted for engagement with said elements, an abutment member mounted on the lever, and a resilient member interposed between said movable and abutment members.

8. The combination in a fluid pressure control valve having a casing and a pair of control valve mechanisms mounted therein each provided with inlet and exhaust valves and a pressure responsive element for actuating said valves, of means for selectively operating said elements including a lever movably mounted in the casing, and means for effecting a yielding force transmitting connection between said lever and elements including a single resilient member carried by said lever.

9. The combination in a fluid pressure control valve having a casing and a pair of control valve mechanisms mounted therein each provided with inlet and exhaust valves and a pressure responsive element for actuating said valves, of means for controlling the operation of said elements including a lever provided with a spherical portion, a socket formed in the casing for receiving said spherical portion, means for effecting a yielding force transmitting connection between said lever and elements including a member slidably mounted on the lever and adapted to engage said elements, an abutment mounted on the lever, and a resilient member interposed between said first named member and abutment, and means for maintaining said lever in valve operating position including a circular groove formed on the surface of said spherical portion and a spring pressed detent carried by the casing and adapted for engagement with said groove.

10. A control valve having a casing provided with a pair of valve mechanisms each having a movable valve operating element, and means for selectively and yieldingly actuating said elements including a lever pivotally mounted on the casing, an actuating member for said elements movably mounted on the lever and adapted for engagement with said elements, an abutment on said lever, and a resilient member interposed between said abutment and actuating member for opposing movement of the latter relative to the

lever on movement of the lever to actuate one or the other of said elements.

11. A control valve having a casing provided with a pair of valve mechanisms each having a movable valve operating element, a lever pivotally mounted in the casing for selectively controlling the operation of said elements, a cover for the casing having a spherical portion formed about the pivotal point of the lever as a center, an opening formed in the spherical portion for permitting movement of the lever, a valve operating member slidably mounted on the lever and adapted for engagement with the elements, a spherically formed closure member slidably mounted on the lever and adapted for engagement and conformity with the inner surface of the spherical portion of said cover for closing the opening regardless of the position of said lever, and resilient means interposed between said valve operating member and closure member for maintaining the latter in engagement with said spherical cover portion and for resiliently opposing movement of said slideable member on the lever on movement of the latter to operate one or the other of said elements.

12. A control valve having a casing provided with a pair of valve mechanisms each having a movable valve operating element, and means for yieldingly and selectively actuating said elements including a lever having a pivotal connection with the casing, means for connecting said lever and elements, and a single resilient member having a connection with the connecting means and a connection with the casing, whereby on movement of the lever to operate one or the other of the elements the resilient means is deflected by an amount substantially proportional to the degree of movement of the lever and a force substantially proportional to amount of deflection of said resilient means is imparted to the operated element through said connecting means.
